Primary Examiner — Katrina A Betton(74) *Attorney, Agent, or Firm* — BEKIARES ELIEZER LLP(57) **CLAIM**

The ornamental design for a vehicle visor as shown and described.

DESCRIPTION

FIG. 1 is a perspective view of a vehicle visor showing my new design;

FIG. 2 is a perspective view thereof;

FIG. 3 is a right side view thereof;

FIG. 4 is a left side view thereof;

FIG. 5 is a front view thereof with the lower portion offset;

FIG. 6 is a back view thereof with the lower portion offset;

FIG. 7 is a top view thereof; and,

FIG. 8 is a bottom view thereof.

The vehicle visor, in various aspects, may be disclosed separately for convenience of illustrations.
